UNITED STATES PATENT OFFICE

WALTER T. JACOBS, OF FREEPORT, ILLINOIS, ASSIGNOR, BY MESNE ASSIGNMENTS, TO
BIG ROCK RANCH COMPANY, OF LOS ANGELES, CALIFORNIA, A CORPORATION OF
CALIFORNIA

HEARSE

Application filed February 14, 1929, Serial No. 339,876. Renewed February 3, 1930.

My invention relates to an improvement in hearse construction, more particularly of the type to deliver the casket through openings at either side of the hearse body.

5 My present invention is a modification of the hearse construction of my pending application for United States Letters Patent Serial No. 319,674, filed November 15, 1928, which relates to a hearse construction in 10 which power-operated mechanism is provided for actuating the platform on which the casket is supported.

My primary object is to provide as a part of the power mechanism a controlling element which, in turn, is controlled by the platform in swinging it out of centralized, normal position in the hearse; and other objects as will be manifest from the following description.

20 Referring to the accompanying drawings:—

Figure 1 is a horizontal plan section of a hearse embodying my invention, the casket-supporting platform being shown in plan, 25 with a portion broken away to disclose certain details of the structure beneath it.

Figure 2 is a view in longitudinal sectional elevation of the structure of Fig. 1, the section being taken at the line 2—2 on Fig. 1 30 and viewed in the direction of the arrows.

Figure 3 is an enlarged cross sectional view taken at the line 3 on Fig. 2 and viewed in the direction of the arrow.

Figure 4 is an enlarged view of the mechanism of Fig. 2 for controlling the clutching of the power device to the drive shaft which actuates the platform.

Figure 5 is a perspective view of the drive mechanism for the platform; and

40 Figure 6, an enlarged sectional view taken at the line 6 on Fig. 5 and viewed in the direction of the arrow.

Referring to the particular construction illustrated, 7 represents the main floor of the hearse body secured by the ordinary means to the hearse chassis 8. 9 is a secondary, or auxiliary, floor parallel with the main floor 7 and spaced a sufficient distance above the latter to provide a space for the platform-operating means hereinafter described.

As shown the auxiliary floor 9 contains a guide slot 10 extending longitudinally of the hearse body and preferably midway between the sides of the latter, the floor 9 also containing a pair of oppositely disposed, laterally extending, reversely curved guide slots 11, which meet at their inner ends at a common point in the longitudinal slot 10 between the ends of the latter, and at their outer ends terminating opposite the openings in the 60 sides of the hearse body and hereinafter referred to.

Immediately above, and parallel with, the auxiliary floor 9 is a casket-supporting platform 12 upon which rests the casket represented at 13, the platform 12 being provided with rollers 14 at its opposite ends to facilitate sliding of the casket from the platform, the platform being movably supported upon the auxiliary floor 9 by a series of ball bearing supports 15.

The casket-supporting platform 12 is adapted to swing the casket forwardly and laterally to permit delivery of the latter through either of the side openings of the 75 hearse body above referred to and represented at 16, these openings being equipped with swinging doors 17.

Depending from the rear portion of the platform 12 is a drive member represented 80 generally at 18 and adapted to move in the longitudinal slot 10, this member being shown in detail in Fig. 6 and comprising a vertical shaft 19 connected at its upper end with the inner raceway 20 of a ball bearing, 85 the outer race-way 21 of which is confined in a housing 22 secured to the underside of the platform 12.

The lower end of the shaft 19 extends through a guide block 23 which is preferably 90 of rectangular shape in plan and extends into the longitudinal slot 10. The lower edge of this block is flanged as represented at 24 at which portion it is provided with a series of ball bearings 25 positioned to contact with the 95 underside of the auxiliary floor 9 when the platform 12 projects outwardly through either of the side openings 16 of the hearse body, the shaft 19 being provided with a head 26 located below the underside of the block 100.

23 to prevent upward displacement of this shaft.

5 The drive member also comprises a nut-forming member secured to, and depending from, the block 23 for cooperation with a drive member hereinafter described. The nut member illustrated comprises a housing 27 secured to the underside of the block 23 with alining openings 28 at its opposite ends, and a removable worm block 29 confined therein, the housing 27 having a depending projection 30 at its front end, for the purpose hereinafter described.

10 The worm block 29 is held in the housing 27 against turning but is slideable therein, coil springs 31 being interposed between the block 29 and the ends of the housing 27 and through which the platform is driven by the block 29.

15 20 Extending through the nut member and engaging the threads of the block 29, is a worm drive shaft 32 located in the space between the floors 7 and 9 and journaled in bearings 33 and 34 on the floor 7, to extend directly below, and parallel with, the guide slot 10, this shaft serving as a means, when operated as hereinafter described, to bodily shift the platform 12 into the desired position.

25 20 Secured to the underside of the casket-supporting platform 12, forwardly of the drive member 18, is a depending lateral guide member 35 which extends through the slotted portion of the floor 9, this guide member being preferably formed of a stud depending from the platform 12 and a roller 37 journaled on this stud and located in the plane of the floor 9.

It may be here stated that the provision of the slots in the floor 9, together with the drive member 18 and the guide member 36, is to permit the platform 12 to be moved into a position substantially at right angles to the length of the hearse with its forward end portion extending laterally outwardly through either of the side openings 16, as desired.

30 In the arrangement shown the guide member 36, when the platform is in the normal full line position shown in Fig. 1, extends coincident with the juncture between the slots 10 and 11, permitting the operator, by swinging the platform 12 at its pivotal connection with the member 23 into a position in which the guide member 36 extends into the inner end of either one of the slots 11 whereby when power is applied to the platform to move it toward the front end of the hearse the guide member 36 will continue its movement along the particular one of the slots 11 into which it was positioned as stated, to cause the forward end of the platform to extend into the right angle position above referred to, the position occupied by the platform when projected through one of the side

openings 16 of the hearse body being that shown in dotted lines in Fig. 1.

35 The drive shaft 32 extends forwardly to the front of the hearse where it is connected by gear mechanism 38 with the armature shaft 39 of an electric motor represented at 40 and shown as located between the floors 7 and 9, a manually operable clutch 41 being interposed at a break in this shaft to permit of its disconnection from the motor 40, if desired.

40 45 The motor 40, which is of a reversible type and the switch mechanism therefor, is of the same construction as that disclosed in my co-pending application above referred to. It will therefore be sufficient to say that the motor is driven in one direction by closing the switch 42 and in the opposite direction by closing the switch 43 each of these switches being of a type comprising a push bar 44 operative, when pushed to the right in Fig. 5, to close the circuit therethrough.

50 55 The switches 42 and 43 are operated through the medium of controlling mechanism comprising a rock shaft 45 shown as journaled in a yoke-shaped bracket 46 secured to the floor 9, the ends of this shaft, preferably deflected as represented at 47, extending into a position accessible to the driver of the car. The shaft 45 has rigid thereon a pair of crescent shaped cams 48 and 49 extending into different angular positions about the shaft 45 and adapted to close the circuit at the normal open switch devices 42 and 43, respectively.

60 65 The operator to shift the platform to a position in which it extends laterally through one of the side openings of the hearse body rotates the shaft 45 in one direction to close one of the switches 42 and 43, the driving of the platform in the reverse direction to move it back to the full line position shown in Fig. 1 being effected by rotating the shaft 45 in the opposite direction to close the other of the switches 42 and 43. The construction shown also comprises means for automatically shifting the shaft 45 to neutral position, in which both of the switches 42 and 43 are open, at either of the limiting positions of the casket-supporting platform 12, these means comprising a stop-control yoke 50 mounted to slide lengthwise of the hearse in guides 51 (one only of which is shown) provided on the floor 7, and pivoted at its forward end to a link 52 which, in turn, is pivoted at its forward end to an arm 53 rigid on the shaft 45, the yoke 50 being provided with a pair of laterally extending spaced apart arms 54 and 55.

70 75 80 85 90 95 100 105 110 115 120 125 The arrangement of the parts is such that assuming the operator rocks the shaft 45 clockwise in Fig. 5 to engage the cam 49 with the switch 43 for closing the circuit which operates the motor 40 in a direction to draw the platform 12 forwardly, in which movement 130

of the shaft 45 the yoke 50 is shifted rearwardly, the arm 55 becomes positioned in the path of forward movement of the projection 30 of the drive member 18 when this guide member approaches a position in which the platform 12 extends substantially at a right angle to the longitudinal axis of the hearse as shown by dotted lines in Fig. 1, whereupon continued forward movement of the drive member 18 shifts the yoke 50 forwardly and rocks the shaft 45 to neutral position and the motor 40 stops.

To return the platform 12 to normal position shown by full lines in Fig. 1, the operator rotates the shaft 45 in counterclockwise direction in Fig. 5 to close the circuit for reversely driving the motor 40, the shaft 45 in this movement moving the yoke 50 forwardly into a position in which the arm 54 extends 20 into the path of rearward movement of the projection 30 on the drive member 18 as the latter nears the limit of its rearward movement in which the platform 12 assumes the position shown in full lines in Fig. 1, the final 25 rearward movement of the member 18 operating to rotate the shaft 45 to neutral position whereupon the motor 40 stops.

An auxiliary, hand-operated, shaft 56 journaled on the hearse body and geared to the shaft 32, by the gears 57 and 58, between the clutch 41 and the drive member 18, is provided to permit of the hand operation of the shaft 32 in case the power mechanism described fails to function, in which case the 35 clutch 41 would be preliminarily released by the operator.

The hearse body is preferably provided at its rear end with an opening 59 controlled by a door 60 and through which the casket may 40 be removed from the hearse, if desired.

For the purpose primarily of preventing the operation of the shaft 45 to a position in which the motor 40 is started for driving the platform forwardly, before the swinging of the platform 12, by the operator, into a position in which the guide member 35 becomes positioned in one of the other of the lateral guide slots 11, I provide a lock device for the shaft 45 which normally locks this shaft 45 against rotation and is automatically released, to permit the shaft 45 to be operated, upon the swinging movement of the platform, as above stated.

The means shown for this purpose comprise a rock shaft 61 journaled in any suitable way to extend into the space between the floors 7 and 9 in a direction crosswise of the drive shaft 32, the shaft 61 being provided with an arm 62 rigid therewith and having a 55 terminal tooth 63 to be received into a peripheral notch 64 in a disk 65 rigidly secured to the shaft 45. Rigidly secured at one end to the shaft 61 is an arm 66 pivotally connected to its other end, as represented at 67, with 60 the lower end of a vertically disposed rod 68

located in alignment with the slot 10 and in a plane between the ends of the platform 12 (considering the latter in the full line position shown in Fig. 1), and slidable in an opening 69 in the floor 9, the upper end of the rod 68 having a rounded head 70 which, in the normal, full line position, (Fig. 1) extends into a socket 71 in the underside of the platform 12.

The bar 68 is yieldingly pressed upwardly, 75 and the arm 62 pressed downwardly to enter the tooth 63 in the notch 64 in the neutral position of the shaft 45 for locking this shaft against rotation, by any suitable means, such, as for example, by the coil spring 72 connected at its upper end with the floor 9 and at its lower end to the arm 66.

It will be understood from the foregoing that in the normal, centralized, position of the platform 12 the shaft 45 is locked against rotation, but upon the swinging of the platform at its front end, by the operator, into a position in which the guide member 35 extends into either of the slots 11, the rod 68 will be automatically pressed downwardly 85 against the action of the spring 72 thereby withdrawing the tooth 63 from the notch 64 and permitting the shaft 45 to be rotated.

It is desirable in a construction of this character that the platform when in normal, centralized, position be held firmly against swinging during the travel of the hearse along the road. In the particular construction shown the rod 68, serves not only to perform the function as above described, but 95 also to prevent such lateral, accidental, swinging of the platform.

Referring to the illustrated means for controlling the clutch 41, such means comprise a clutch sleeve 73 splined to, and slidable 105 along, one of the shaft sections 32 and engaged by a yoke bar 74 pivoted at 75 to a bracket 76 secured to the underside of the floor 9 and pressed by a spring 77 into clutching position. The upper end of the bar 74 110 extends opposite to, and is engaged by, the peripheral portion of a cam 78 fixed on the lower end of a shaft 79 rotatable in the floor 9 and provided at its upper end with an arm 80 by which the cam may be rotated to withdraw the clutch element 73 from clutching 115 position.

While I have illustrated and described a particular construction embodying my invention, I do not wish to be understood as intending to limit it thereto as the same may be variously modified and altered without departing from the spirit of my invention.

What I claim as new, and desire to secure by Letters Patent, is:

1. In a hearse of the side-delivery type, a platform, power-operated means for moving said platform lengthwise of the hearse, said platform being adapted to swing at one end toward a side of the hearse, a laterally 130

- extending guide engageable by a portion of said platform, and controlling means for said power-operated means comprising a controlling element actuated by said platform in the swinging of the latter toward a side of the hearse.
2. In a hearse of the side-delivery type, a platform, power-operated means for moving said platform lengthwise of the hearse, said platform being adapted to swing at one end toward a side of the hearse, a laterally extending guide engageable by a portion of said platform, and controlling means for said power-operated means comprising a controlling element actuated by said platform in the swinging of the latter toward a side of the hearse and serving to releasably lock said platform against accidental swinging out of normal position.
3. In a hearse of the side-delivery type, a platform, power-operated means for moving said platform lengthwise of the hearse, said platform being adapted to swing at one end toward a side of the hearse, a laterally extending guide engageable by a portion of said platform, and controlling means for said power-operated means comprising a locking element actuated out of locking position by said platform in the swinging of the latter toward a side of the hearse.
4. In a hearse of the side-delivery type, a platform, power-operated means for moving said platform lengthwise of the hearse, said platform being adapted to swing at one end toward a side of the hearse, a laterally extending guide engageable by a portion of said platform, and controlling means for said power-operated means comprising a locking element actuated out of locking position by said platform in the swinging of the latter toward a side of the hearse, said locking element also operating to releasably lock said platform against accidental swing out of normal position.
5. In a hearse of the side-delivery type, a platform, power-operated means for moving said platform lengthwise of the hearse, said platform being adapted to swing at one end toward either side of the hearse, guides extending laterally in opposite directions and engageable by a portion of said platform, and controlling means for said power-operated means comprising a controlling element actuated by said platform in the swinging of the latter.
6. In a hearse of the side-delivery type, a platform, power-operated means for moving said platform lengthwise of the hearse, said platform being adapted to swing at one end toward either side of the hearse, guides extending laterally in opposite directions and engageable by a portion of said platform, and controlling means for said power-operated device comprising a controlling element actuated by said platform in the swinging of the latter and serving to releasably lock said platform against accidental swinging out of normal position.
7. In a hearse of the side-delivery type, a platform, power-operated means for moving said platform lengthwise of the hearse, said platform being adapted to swing at one end toward either side of the hearse, guides extending laterally in opposite directions and engageable by a portion of said platform, and controlling means for said power-operated means comprising a locking element actuated by said platform in the swinging of the latter.
8. In a hearse of the side-delivery type, a platform, power-operated means for moving said platform lengthwise of the hearse, said platform being adapted to swing at one end toward either side of the hearse, guides extending laterally in opposite directions and engageable by a portion of said platform, and controlling means for said power-operated means comprising a locking element actuated by said platform in the swinging of the latter and operating to releasably lock said platform against accidental swinging out of normal position.
